America as represented by the Secretary of the
Navy

Application June 3, 1952, Serial No. 291,409

5 Claims. (Cl. 250—27)

1

This invention relates to means for a method of comparing the synchronism of two reoccurring voltages and for providing a control voltage directly proportional to a difference in synchronism of the two voltages. More particularly, the invention relates to a circuit for providing a control voltage proportional to a difference in synchronism of a gate voltage of a given frequency and of a sawtooth voltage approximately of the same frequency.

The gate voltage which is a rectangular voltage wave and is to be compared in synchronism with a sawtooth voltage wave is applied to the anodes of a pair of electron tubes. The control electrode in one of these tubes is at ground potential and both electron tubes are cut-off until the gate voltage in amplified form is applied to the anodes thereof. The control electrode of the other of the electron tubes has the sawtooth voltage applied thereto. The sawtooth voltage wave is so constituted that, at the beginning of each cycle, the voltage rises linearly to a peak at the end of the cycle and then falls almost instantaneously to a negative maximum at the beginning of the cycle. Centrally of the sawtooth voltage wave the voltage is made to pass through zero potential, at which point the control electrode of the second electron tube is also at ground potential.

A control pulse either positive or negative occurs if the gate voltage applied to the anodes of the electron tubes differs in time from the time at which the control electrodes of both electron tubes are at ground potential, at which time the gate voltage is synchronized with the sawtooth voltage. The control pulse formed by comparing the synchronism of the gate and the sawtooth voltage is negative when the gate deviates to the positive portion of the sawtooth voltage, and is positive when the gate deviates to the negative portion of the sawtooth voltage.

An object of the invention is electronically without moving parts to compare the synchronism of two voltages and provide a control voltage.

A further object of this invention is to compare the synchronism of two voltages approximately of the same frequency and to provide a control voltage directly proportional to a difference in synchronism of the two voltages.

And an additional object of this invention is to compare the synchronism of a gate and sawtooth

2

voltage and to provide a pulse for forming a control voltage when the gate deviates from the zero potential of the sawtooth voltage.

The invention as to organization and manner of operation together with further objects and advantages thereof may best be understood by reference to the following detailed description taken in connection with the accompanying drawing wherein Figure 1 is a circuit diagram showing the electronic elements of the invention in a preferred embodiment; Figure 2 is a graph of the voltage-time wave shapes of the circuit of Figure 1 when the comparing electron tubes gate in synchronism with the zero potential point of the sawtooth voltage appearing on the control electrode of the second electron tube; Figure 3 is a graph of the voltage-time wave shapes of the circuit of Figure 1 when the comparing electron tubes gate at a time when the positive portion of the sawtooth voltage appears on the control electrode of the second electron tube; and Figure 4 is a graph of the voltage-time wave shapes of the circuit of Figure 1 when the comparing electron tubes gate at a time when the negative portion of the sawtooth wave appears on the control electrode of the second electron tube. Identical circuit features in each figure have been designated with the same numerical identification.

Referring particularly to Figure 1, the electronic circuit comprises a diode 1, the anode 2 of which passes a negative gate voltage 3 to the control grid 4 of a first pentode tube 5 which gate voltage is compared in synchronism with a sawtooth voltage 6 from a sweep generator 7.

The pentode tube 5 having an anode 8 and cathode 9 is operating as a class A amplifier and is normally conducting, and has an anode to cathode circuit connected between ground and a source of positive potential 58 through the anode load resistance 10. The screen grid 11 of pentode 5 is connected to a source of positive potential 51 and the control grid 4 is connected to the anode 2 of diode 1 and through the grid resistor 12 to ground.

The diode 1 offers a low reactance to the negative gate voltage 3 and the grid resistor 12 is of large value so that the shunting effect of the grid resistor 12 is small. During intervals between gating voltage pulses the pentode 5 conducts considerable anode current and the voltage drop across the anode load resistance 10 is large. The

negative gate voltage 3 which is applied to the control grid 4 cuts off the pentode tube 5 for the duration of the gate voltage and the anode current of pentode tube 5 drops. The voltage drop across anode load resistance 10 therefore decreases and the voltage at anode 8 increases to equal the voltage of the source 50.

A pair of electron tubes 13 and 14 which have anodes 15 and 16 respectively connected to the anode 8 of pentode tube 5 comprise the voltage comparison circuit for comparing the synchronism between the gate voltage 3 and the sawtooth voltage 6. The control electrode 17 of electron tube 13 is connected to ground, and the control grid 18 of electron tube 14 is connected to the sawtooth voltage 6 appearing across cathode resistor 19 of the tube 20.

The sawtooth generator produces a voltage which increases linearly with time during the cycle from a minimum voltage to a maximum voltage and then decreases almost instantaneously to the minimum voltage to begin a new cycle. This voltage is impressed on the control grid 20a of the cathode follower tube 20, the anode 20b of the tube 20 being connected to a source of positive voltage 52 and the cathode 20c being connected to a source of negative voltage 53 through the potentiometer 19. Since the source of negative potential is considerably below ground potential, the cathode 20c may vary over a wide range from below ground potential to above ground potential and a corresponding voltage appears across the potentiometer 19. A portion of this voltage is impressed on the grid 18 of tube 14, the proportion being determined by the setting of the potentiometer 19 which acts to vary the point in the cycle of the sawtooth wave at which the voltage on the grid 18 is equal to ground potential. The potentiometer 19 therefore serves as a phasing control for the circuit.

The cathodes 21 and 22 of the electron tubes 13 and 14 are connected to ground through the equal cathode resistances 23a and 24, the cathode 21 being connected to the cathode 25 of the tube 27 through the cathode resistance 23b. As will be hereinafter explained in more detail, the current conducted by tube 27 is conducted through resistance 23a and provides a negative bias on the grid 17 with respect to the cathode 21.

The cathode 22 of the tube 14 is raised to a positive potential by means of a source of positive potential by a circuit extending from the source in positive potential 54 through the variable resistance 29 and resistance 24 to ground. The variable resistance 29 is adjusted to make the voltage drop thus produced across the resistance 24 equal to the voltage drop produced across the resistance 23a by the current conducted by tube 27 when the tube 27 is conducting normally, so as to balance the conduction characteristics tubes 13 and 14.

During the time interval between gating voltage pulses, the pentode tube 5 conducts heavily, since its control grid 4 is not biased negative with respect to its cathode, and the current conducted by the pentode tube 5 through the load resistance 10 produces sufficient voltage drop across the resistance 10 to reduce the voltage at the anodes 8, 15 and 16 to about 25 volts. The cathodes 21 and 22 of the tubes 13 and 14 are raised above ground potential by the circuit as previously explained sufficiently to prevent conduction of the tubes 13 and 14. However, when the gate voltage pulse is impressed on the grid

4 of the pentode 5 to momentarily prevent conduction therethrough, the voltage applied to the anodes 15 and 16 rises sufficiently to render these tubes conductive and therefore responsive to the potentials impressed on their respective grids. If the potentials on the respective grids of tubes 13 and 14 are equal at the time the gating voltage pulse is impressed on the grid 4 of tube 5, the conduction of tubes 13 and 14 are equal as are the voltages on their respective cathodes. However, if the potentials on the grids 17 and 18 with respect to ground are unequal, the tube having the more positive grid potential will conduct more heavily and its cathode will therefore be raised more positive than the cathode of the other.

The tube 27 is connected to amplify the difference in voltage produced between the cathodes 21 and 22 by any inequality in conduction of the tubes 13 and 14. As described herein, the tube 27 is a sharp cut-off pentode to provide high gain and sensitivity, but it will be readily apparent to those skilled in the art that a wide variety of tubes could be employed if desired. As previously mentioned the cathode 21 of tube 13 is connected to the cathode 25 of tube 27 through the resistance 23, the resistance 23 being paralleled by the capacitor 33 which prevents rapid changes in the voltage appearing across the resistance 23b. The suppressor grid 28 is connected to the cathode 25, and the control grid 26 is connected to the cathode 22 of tube 14, while the anode 35 is connected to the source of positive potential 55 through the load resistance 36.

The operating characteristic of the pentode tube is affected in large measure by the voltage difference between its cathode and screen grid, and in the present application the potential of the cathode 25 of tube 27 is periodically raised by an appreciable amount of application of a gate voltage pulse to the pentode 5. In order to stabilize the operation of tube 27, the voltage impressed on its screen grid 30 relative to its cathode 25 is maintained substantially constant by means of the series dropping resistance 31 connecting the source of positive potential 54 to the screen grid 30 and the neon regulator tube 32 connected between the screen grid 30 and the cathode 25.

The operation of the voltage regulator circuit comprising the dropping resistance 31 and the neon regulator tube 32 is conventional. When the voltage impressed on the tube 32 increases, the current conducted by the tube increases and thereby increases the voltage drop produced across the resistance 31 to reduce the potential impressed on the screen grid 30. A voltage decrease will produce an opposite action.

The output voltage of the anode 35 of tube 27 is impressed through coupling resistances 39 and 40 on the resistances 41 and 42 respectively, so that equal pulsating voltages appear across the resistances 41 and 42. The positive pulsations of the voltage appearing across the resistance 41 are rectified by the diode 37, while negative pulsations appearing across the resistance 42 are rectified by the diode 38, and since the pulsations as hereinafter explained occur in only one direction at a particular instant, the output diodes 37 and 38 is a direct current voltage having a polarity magnitude determined by the magnitude and polarity of the potential difference between the cathodes 21 and 22 at the instant the gate voltage pulse is impressed on the pentode 5.

A positive pulse forms when the electron tubes

13 and 14 are gated and the control grid 18 of the electron tube 14 is negative, i. e., the electron tubes 13 and 14 are gated during the negative portion of the sawtooth voltage 6. A negative pulse voltage forms when the electrode tubes 13 and 14 are gated and the control electrode of the electron tube 14 is positive, i. e., the electron tubes 13 and 14 are gated during the positive portion of the sawtooth voltage 6.

A storage network or filter 48 from the lead 47 connected with the diodes 37 and 38 respectively to ground provides smoothing to the control voltage when a positive or negative pulse is passed by the valve 37 or 38 indicating that the gate voltage 3 is not synchronized with the zero potential point of the sawtooth voltage 6. Typically filter 48 may be a large capacity condenser capable of retaining considerable energy.

The gate voltage 3 is shown in each of Figures 2, 3, and 4 which illustrate graphically the changes in circuit conditions when the electron tubes 13 and 14 are gated. The gate voltage 3 is shown as a function of time and reoccurs at approximately the same time intervals. Beginning at zero time, the sawtooth voltage 6 is also illustrated as a reoccurring voltage of the same frequency as the gate voltage 3. When these voltages are synchronized, the control voltage of curve "a" of Figure 2 appears at the anode 35 of the tube 27. The condition whereby the electron tubes 13 and 14 are gated at a time at which the control grid 18 of the electron tube 14 is at a positive potential is illustrated in Figure 3, and the negative voltage pulse illustrated in curve "b" appears at the anode 35 of the pentode 27; likewise the condition whereby the electron tubes 13 and 14 are gated at a time at which the control grid 18 of the electron tube 14 is at a negative potential is illustrated in Figure 4, and the positive voltage pulse illustrated in curve "c" appears at the anode 35 of the pentode 27.

The circuit of Figure 1 operates to provide a positive or negative voltage pulse directly proportional to the difference in synchronism of the gate voltage 3 pulse indicated by and the sawtooth voltage 6. The electron tubes 13 and 14 compare the synchronism of the two wave indicated by voltages and the control grid-to-cathode circuit of the tube 27 changes potential if a difference in synchronism exists. The change of potential in the control grid-to-cathode circuit of tube 27 changes the conductivity of the tube 27. The control grid-to-cathode voltage of the tube 27 is stabilized during the interval between gating voltage pulse.

The control grid 17 of electron tube 13 is at ground potential and the control grid 18 of electron tube 14 is at ground positive, or negative potential dependent upon the phase and synchronism of the sawtooth voltage wave 6 and the gate voltage wave 3.

It is of course to be understood that the voltage pulse from the anode 35 of the tube 27 may be used directly or filtered by a filter 48 to provide a direct current control voltage for synchronizing the gate voltage wave 3 and the sawtooth voltage wave 6, and that ordinarily only a small portion of the gate voltage 3 is needed to provide the voltage pulses used to provide a synchronous condition.

While a particular embodiment of the invention has been illustrated and described, it will be obvious to those skilled in the art that changes and modifications may be made without departing from the invention in its broader aspects.

For example, the voltage pulses or control voltage may be applied to control an oscillator frequency, a motor speed, or other device, and it is therefore an aim in the appended claims to cover all such changes and modification as fall within the true spirit and scope of this invention.

What is claimed as new is:

1. A circuit for comparing the synchronism of two reoccurring voltages of approximately the same frequency to provide a voltage directly proportional to a difference in synchronism of said voltages comprising, in combination, a normally conducting electron tube having an anode, control electrode and cathode, an anode resistor connected to said anode of said normally conducting electron tube and to a source of anode voltage, whereby conduction of said normally conducting electron tube reduces the anode voltage thereof, a source of sawtooth voltage having a zero potential point centrally of the sawtooth, a first and second electron tubes each having an anode, a cathode, and a control grid, said anodes being connected in parallel with the anode of said normally conducting electron tube and said control grids being connected respectively to zero potential and to said sawtooth voltage, means connected to the cathodes of said first and second electron tubes for normally biasing said first and second electron tubes to cut-off, a gate voltage, means for applying said gate voltage to said normally conducting electron tube thereby to raise the anode voltage of said paralleled anodes for the duration of said gate voltage to render conductive said first and second electron tubes, and current comparing means for measuring the difference in conduction of said first and second electron tubes and for providing a control voltage proportional to said difference in conduction.

2. The circuit of claim 1 in which the current comparing means comprises a pentode tube having a stabilized screen grid-to-cathode voltage and a control grid-to-cathode circuit connected to said first and second electron tubes to receive a voltage therefrom proportional to the difference in conduction of said first and second electron tubes during the conduction thereof.

3. The circuit of claim 1 in which the current comparing means comprises a third electron tube having a cathode and a control grid connected to the respective cathodes of said first and second electron tubes, whereby the conduction of said third electron tube varies with the difference in conduction between said first and second electron tubes.

4. A circuit for comparing the synchronism of a source of rectangular voltage and a source of sawtooth voltage comprising a first and a second electron tube each having at least an anode, a cathode and a control grid, means connecting the anodes of said first and second electron tubes to each other and to an anode resistor, means connecting said anode resistor to a source of anode power, individualized resistor means connecting said cathodes of said first and second electron tubes to ground, a normally conducting electron tube having its anode connected to the anodes of said first and second electron tubes whereby conduction of said normally conducting electron tube reduces the anode voltage of said first and second electron tubes, means connecting the control grids of said first and second electron tubes to ground and to the source of sawtooth voltage respectively, means impressing the voltage from the rectangular voltage source on said normally conducting electron tube to render it non-conductive thereby

to render said first and second electron tubes conductive, and comparison means connected to the respective cathodes of said first and second electron tubes to produce a voltage proportional to the difference between the conduction of said first and second electron tubes.

5. The circuit as claimed in claim 4 wherein said comparison means comprises a third electron tube having a cathode and a control grid connected to respective ones of the cathodes of said first and second electron tubes, whereby the

conduction of said third electron tube varies with the difference in conduction between said first and second electron tubes.
